FILTER FOR FLUIDS

George Payne, Bedford Hills, N.Y., assignor to American
Machine & Foundry Company, a corporation of New
Jersey

Filed May 4, 1966, Ser. No. 2,155

Term of patent 14 years

(Cl. D91—1)

The figure is a perspective view of the filter for fluids showing my new design.

The side opposite is similar in appearance. The dominant features reside in the solid line portions.

I claim:

The ornamental design for a filter for fluids, as shown and described.
